ANTOINE DE LOTBINIERE PANET, OF TORONTO, ONTARIO, CANADA.

COMBINED SLEEPING-BAG AND SHELTER.

1,195,394.

Specification of Letters Patent. Patented Aug. 22, 1916.

Application filed September 27, 1915. Serial No. 52,897.

To all whom it may concern:

Be it known that I, ANTOINE DE LOTBINIERE PANET, of the city of Toronto, in the county of York, in the Province of Ontario, Canada, have invented certain new and useful Improvements in Combined Sleeping-Bags and Shelters, of which the following is the specification.

My invention relates to improvements in combined sleeping bags and shelters and the object of the invention is to provide a shelter formed integral with the sleeping bag and readily portable therewith and which may be quickly and easily set up whenever required over the bag when in use and it consists essentially of a sleeping bag provided with a haversack secured in the mouth of the bag so as to form a pillow when filled, an extension to the bottom portion of the bag foldable intermediately of its length, means for securing the outer edge of the extension to the opposite side of the bag and means for supporting the center or foldable portion of the extension centrally above the bag to form a shelter as herein-after more particularly explained by the following specification.

Figure 1, is a perspective view of my bag and shelter laid out flat. Fig. 2, is a perspective view showing the application of my combined bag and shelter. Fig. 3, is a cross sectional view showing the bag laid out flat in full lines and the position in which it is used by dotted lines.

35 In the drawings like letters of reference indicate corresponding parts in each figure.

1 indicates a sleeping bag proper provided with the usual mouth 2 and laced opening 3.

40 4 indicates a haversack secured in the mouth of the bag and provided with a closing flap 5. The bag when filled with clothing or other suitable material serves as a pillow for the sleeper.

45 5 6 indicates an extension which may be formed integral with the bottom of the bag or secured thereto along one edge thereof. The center portion of the extension 2 is provided with a longitudinal hem 7 through 50 which a cord 8 extends.

10 indicates a flap secured to the opposite

edge of the bottom of the sleeping bag and provided with dome fasteners or other suitable securing means 11.

12 and 13 indicate crossed stakes which are driven into the ground and connected together at 15. Although I have shown cross stakes it will, of course, be understood that cross rifles might be used in place thereof.

When it is desired to use the shelter all that it is necessary to do is to insert the stakes 12 and 13 in the ground at each end of the sleeping bag, throw the extension 6 up, pass the cord 8 through the crotches formed by the stakes 12 and 13 securing the lower ends of the cord to suitable pegs 17. The free end of the extension is then secured by the dome fasteners 11 to the flap 10 thereby completing the shelter. The extension 6 may be formed of any suitable water proof material such as water proof silk and such as will be light, strong and durable.

In order to prevent a draft passing through the shelter I utilize the closing flap of the haversack which is carried to close the end of the shelter and secured by suitable means to the extension piece 6 as indicated by dotted lines in Fig. 2.

What I claim as my invention is:

1. In a sleeping bag, the combination with the bag body having a bag-like portion extending from the lower edge of the mouth of the bag body, a fabric portion extending from one longitudinal edge of the bag body, means for supporting the fabric extension in an inverted V-form over the bag body, means for detachably securing the outer free end of the fabric portion to the opposite longitudinal edge of the bag body, and a flap normally forming a cover for the bag extension and adapted to be secured to the inverted V fabric portion when desired.

2. In a sleeping bag, the combination with the bag body having a bag-like portion secured to the upper face and extending from the lower edge of the mouth of the bag body, a fabric portion extending from one longitudinal edge of the bag body, means for supporting the fabric portion in an inverted V form over the bag body, means for

detachably securing the outer free end of the fabric portion to the opposite longitudinal edge of the bag-body, and a flap extending from the lower edge of the mouth of the bag-like portion for simultaneously forming a closure for the mouth of the bag-like por-

tion and a closure for the corresponding end of the inverted V portion.

ANTOINE de L'OTBINIERE PANET.
